US00D955676S

(12) **United States Design Patent** (10) **Patent No.:** **US D955,676 S**
(45) **Date of Patent:** **** Jun. 21, 2022**

(54) **HAMPER**

(71) Applicant: **LG ELECTRONICS INC.**, Seoul (KR)

(72) Inventors: **Hana Choi**, Seoul (KR); **Eunsil Mok**, Seoul (KR); **Jinsu Kim**, Seoul (KR); **Taewoo Yoo**, Seoul (KR); **Yousook Eun**, Seoul (KR); **Soonho Jung**, Seoul (KR)

(73) Assignee: **LG ELECTRONICS INC.**, Seoul (KR)

(**) Term: **15 Years**

(21) Appl. No.: **35/509,800**

(22) Filed: **Feb. 20, 2019**

(80) **Hague Agreement Data**

Int. Filing Date: **Feb. 20, 2019**

Int. Reg. No.: **DM/209040**

Int. Reg. Date: **Feb. 20, 2019**

Int. Reg. Pub. Date: **Jul. 17, 2020**

(51) **LOC (13) Cl.** 23-99

(52) **U.S. Cl.**

USPC **D34/1**

(57) **CLAIM**

The ornamental design for a hamper, as shown and described.

DESCRIPTION

1. Hamper

1.1 : Perspective

1.2 : Front

1.3 : Back

1.4 : Left

1.5 : Right

1.6 : Top

1.7 : Bottom

1.8 : Perspective view showing the hamper with the door in a partially open position. The broken line showing of a robot depicts environmental subject matter which forms no part of the claimed design.

1.9 : Perspective view showing the hamper with the door in a fully open position. The broken line showing of a robot depicts environmental subject matter which forms no part of the claimed design.

The broken lines depict environmental subject matter and portions of the hamper that form no part of the claimed design.

1 Claim, 9 Drawing Sheets
